US00D690553S

(12) **United States Design Patent**
Tosdale et al.

(10) **Patent No.:** **US D690,553 S**
(45) **Date of Patent:** **** Oct. 1, 2013**

(54) **FOOD PAN**

(71) Applicant: **The Vollrath Company, L.L.C.**,
Sheboygan, WI (US)

(72) Inventors: **David R. Tosdale**, Manitowoc, WI (US);
Theresa M. Mayer, Sheboygan, WI
(US)

(73) Assignee: **The Vollrath Company L.L.C.**,
Sheboygan, WI (US)

(**) Term: **14 Years**

(21) Appl. No.: **29/444,967**

(22) Filed: **Feb. 6, 2013**

206/501-505, 507-508; 219/386, 400, 405,
219/429-442, 450.1, 452.13, 460.1, 620-624,
219/725, 730-735; 220/4.24, 23.8, 315,
220/573.1-573.5, 629, 743, 756, 769, 912;
426/438, 441, 549

See application file for complete search history.

(57) **CLAIM**

We claim the ornamental design for a food pan, as shown and described.

DESCRIPTION

FIG. 1 is a front perspective view from above of the claimed design;

FIG. 2 is a front view of the claimed design;

FIG. 3 is a right side view of the claimed design;

FIG. 4 is a rear view of the claimed design;

FIG. 5 is a left side view of the claimed design;

FIG. 6 is a bottom view of the claimed design; and,

FIG. 7 is a top view of the claimed design.

The broken lines in the drawings are for illustrative purposes only and form no part of the claimed design.

1 Claim, 7 Drawing Sheets
